FIG. 1 is a perspective view of a jar or the like showing my new design;

FIG. 2 is an elevational view;

FIG. 3 is a bottom plan view;

FIG. 4 is a top plan view; and

FIG. 5 is a vertical sectional view.

The characteristic features of my design reside in the combination of a closure and a jar of the same diameter and height together with a recessed top and inset base all as shown.

I claim:

The ornamental design for a jar or the like, substantially as shown and described.
